UNITED STATES PATENT OFFICE

CHARLES CHAMBERLAIN, OF NEW YORK, AND CHARLES MAGEE, OF BROOKLYN, N. Y., ASSIGNEES TO THE BIGELOW CARPET COMPANY, OF CLINTON, MASSACHUSETTS.

DESIGN FOR CARPET-BORDER.

SPECIFICATION forming part of Design No. 12,181, dated March 1, 1881.

Application filed January 22, 1881. Term of patent 3½ years.

To all whom it may concern:

Be it known that we, CHARLES CHAMBERLAIN, of the city, county, and State of New York, and CHARLES MAGEE, of the city of Brooklyn, county of Kings, and State of New York, have invented a new and original Design for a Carpet-Border, of which the following is a specification.

This invention relates to a new and original design for carpets and similar fabrics; and it consists in the novel grouping and configuration of figures, hereinafter more fully described.

The accompanying photograph illustrates a face view of a carpet-border having our new design.

The figure A is a rustic bridge, over one parapet of which appears to hang a bunch of roses and buds, while over the other parapet hangs a leafy vine. The figure B, a portion of which appears at the left-hand side of the photograph, is composed of a bunch of widely-open flowers, from which extends a bunch of roses, the whole being surrounded and filled in with leaves and foliage. From the figure B extends into the stripe D a figure, a, composed of a bunch of three tulip-like flowers standing on slender stems. The stripe D has upon it a portion of each of the figures b set at regular intervals, each figure b crossing the stripe E and running into the stripe F, and serving as a support for the figure d in that stripe. The figures b are connected with each other by zigzag bands within the stripe D which borders the ornamental figures A and B, already described. The stripe C, which serves as the lower border of the figures A and B, is composed of a series of narrow ornamented bands, as shown in the photograph. Above the stripe D runs the stripe E, ornamented with a regular pattern of alternate circular and cross-like figures, and above this stripe E runs the stripe F, orna-

mented with the rosette-shaped figures d, placed at regular intervals and alternating with tulip-like figures e, also placed at regular intervals along the stripe. Each figure d stands upon a figure, b, already described, the two figures b and d making a compound figure, b d.

We claim—

1. The design for carpets, consisting of the figures A and B, substantially as shown. 50
2. The design for carpets, consisting of the figures A, B, and a, substantially as shown.
3. The design for carpets, consisting of the stripe D, substantially as shown.
4. The design for carpets, consisting of the stripe C, substantially as shown. 55
5. The design for carpets, consisting of the stripe E, substantially as shown.
6. The design for carpets, consisting of the stripe F, containing the figures d and e, substantially as shown. 60
7. The design for carpets, consisting of the figures b and d, substantially as shown.
8. The design for carpets, consisting of the figure e, substantially as shown. 65
9. The design for carpets, consisting of the stripe F, containing figures d and e, the stripe E, and the stripe D, containing a portion of the figure b, substantially as shown.
10. The design for carpets, consisting of the stripe D, figures A and B, and the stripe C, substantially as shown. 70
11. The design for carpets, consisting of the stripe F, containing figures d and e, the stripe E, stripe D, figure b, the figures A, B, and a, and the stripe C, substantially as shown. 75

CHARLES CHAMBERLAIN.
